FLUID PRESSURE ACTUATED SWITCH

Gilbert H. Hansen, Batavia, Ill., assignor to Fur-
nas Electric Company, Batavia, Ill., a corpora-
tion of Illinois

Application April 8, 1950, Serial No. 154,799

18 Claims. (Cl. 200—81.5)

1

My present invention relates generally to improvements in electric switches, and relates more specifically to various improvements in the construction and operation of fluid pressure actuated electric toggle switch assemblages.

The primary object of the present invention is to provide an improved fluid pressure actuated electric switch which is simple and compact in construction, and which is moreover highly efficient in operation.

Many different types of fluid pressure operated electric switches have heretofore been proposed and utilized for diverse purposes, and in some of these prior switch assemblages the contacts were presumably opened and closed with a snap action by means of toggle and spring mechanism activated by variations in the pressure of the operating fluid. In the prior toggle switches most extensively used, the contact actuating toggle links were rigid and were snapped from one extreme position to another with the aid of coil springs, and in these mechanisms the rigid toggles would frequently hang on dead center thus making it difficult to obtain the impact blows necessary for positive and quick closing and separation of the switch contacts. Then too, the prior rigid toggle mechanisms would tend to wear rapidly and thereby introduced inaccurate functioning of the switches, and they also failed to insure sufficient contact closing pressure so as to properly carry the starting current of the motor or other equipment with which the switches were associated. These prior switches were also objectionable due to their relatively complicated construction, and because of the fact that adjustment of the actuating pressure ranges could not be accomplished with sufficient precision, thus making the prior fluid pressure actuated switches unsatisfactory for diverse reasons.

It is therefore an important object of my present invention to provide an improved snap-action toggle switch which obviates all of the above-mentioned objectionable features, and which embodies a highly sensitive and reliable actuating toggle mechanism.

Another important object of this invention is to provide a simplified and durable spring toggle assemblage, which will insure proper snap-action of the relatively movable switch contacts so as to positively close and open these contacts at all times and while under the influence of variable fluid pressures.

A further important object of the invention is to provide an improved multiple leaf-spring toggle mechanism for fluid pressure actuated

switches, wherein the resilient toggle links or elements will definitely produce the hammer blows requisite in order to assure sufficient snap-action at the contacts, regardless of the position or setting of the pressure range varying mechanism.

Still another important object of my invention is to provide an exceedingly compact pressure actuated switch assembly comprising a relatively few simple but sturdy parts, which may be readily constructed, assembled and dismantled, while also being safely conveniently accessible for inspection and adjustment.

An additional important object of the present invention is to provide a toggle switch operable by fluid pressure, wherein sufficient adjustment is provided for normal wide ranges of variation of differential and pressure settings, and which will also amply compensate for inaccuracies such as might result from mass production of parts.

Another important object of this invention is to provide an improved switch toggle mechanism in which the toggle elements are adapted to be snapped into operating position and are maintained in such position without the aid of additional fastening means, and wherein the parts are constructed of durable special materials capable of most effectively resisting undesirable wear and tear.

A further important object of my present invention is to provide an improved well insulated electric switch unit of utmost precision and dependability having all elements amply protected against damage, and which may be manufactured and sold for diverse uses at moderate cost.

These and other more specific objects and advantages of the invention will be apparent from the following detailed description.

A clear conception of the novel features constituting my present improvement, and of the construction and operation of a typical fluid pressure actuated switch unit embodying the same, may be had by referring to the drawings accompanying and forming a part of this specification and wherein like reference characters designate the same or similar parts in the various views.

Fig. 1 is a top view of one of the improved pressure actuated switch units with the top cover removed;

Fig. 2 is a central longitudinal section through the completely assembled unit, the section having been taken along the line 2—2 of Fig. 1;

Fig. 3 is a side elevation of the same switch

unit but with the casing, cover and fluid pressure applying mechanism omitted;

Fig. 4 is an end view of the portion of the switch unit shown in Fig. 3, with a portion of the guard plate broken away;

Fig. 5 is an opposite end view of the same portion of the mechanism which is shown in Fig. 3;

Fig. 6 is a reduced transverse section through the terminal block or board of the switch, taken along the line 6-6 of Fig. 3;

Fig. 7 is a similarly reduced transverse section through the terminal board of the unit, taken along the line 7-7 of Fig. 3; and

Fig. 8 is a reduced top view of the fluid pressure transmitting stirrup and its retainer element.

The gist of my present invention is the provision of a highly sensitive and dependable leaf-spring toggle for insuring positive closing and opening of the contacts of a fluid pressure actuated switch with an impact snap-action, and while the invention has been shown by way of illustration as being advantageously applicable to a double-contact electric switch unit for controlling the starting and stopping of a motor, it is not my desire or intent to unnecessarily restrict the utility of the improved features by virtue of this limited embodiment. It is also contemplated that specific descriptive terms employed herein be given the broadest possible interpretation consistent with the actual disclosure.

Referring to the drawings, the improved fluid pressure actuated electric toggle switch unit shown therein comprising in general, a main frame 10 having a base 11 provided with integral opposite side walls 12 and an intervening end wall 13; a rigid lever 14 having one end portion provided with integral side pivots 15 swingably coacting with notches 16 in the side walls 12 of the frame 10 while its opposite swinging end is provided with laterally spaced hooks 17; a flexible diaphragm 18 cooperating with a stirrup plate 19 having upstanding side projections 20 coacting with sockets formed in the medial portion of the lower face of the lever 14; an elongated stiffened toggle plate 21 having a longitudinal edge 22 swingably cooperable with the hooks 17 of the lever 14; a flexible toggle link or leaf spring 23 pivotally coacting with each of the opposite ends of the plate 21 near the spaced hooks 17 but remote from the pivot edge 22, the ends 24 of the toggle leaf springs 23 remote from the plate 21 being pivoted in sockets 25 formed in the frame wall 13; a terminal board 26 firmly but detachably secured to the ends of the frame walls 12 remote from the base 11 by means of screws 27, and having two fixed contacts 28 mounted thereon above the hooks 17; movable contacts 29 carried by spring arms 30 secured to the board 26 remote from the fixed contacts 28 but being cooperable with the latter; a reciprocable rod or bar member 31 operatively connecting the swinging medial portion of the toggle plate 21 with the movable contact carrier arms 30 near the contacts 29; and an adjustable compression spring 32 coacting with the medial portion of the upper face of the lever 14.

The main frame 10 with its integral bottom 11, side walls 12 and end walls 13 may be formed of a single piece of sheet metal with the aid of punches and dies, and the terminal board 26 which spans and is firmly but detachably secured to the frame walls 12 by means of

the screws 27, is formed of insulation and provides a rigid connection between these walls 12. The frame 10 and contact carrier board 26 may be housed as a unit within a durable sheet metal casing 34 having therein one or more openings 35 for the electrical conductors, and the flexible diaphragm 18 may be firmly clamped to the bottom of the housing 34 by an enclosure 36 held in place by the same screws or other fasteners which normally hold the frame 10 in proper position within the casing 34. The casing 34 is also preferably provided with a durable sheet metal cover 37 which may be detachably secured to the terminal board by means of a single stud 38 coacting with a threaded opening 39, and the lower enclosure 36 cooperates with a pulsation eliminator 40 and with a fluid supply nut 41 to provide a fluid pressure chamber 42 beneath the flexible diaphragm 18, see Figs. 1 and 2.

The rigid lever 14 and the fluid pressure transmitting stirrup 19 may also be formed of durable relatively heavy sheet metal with the aid of punches and dies; and besides the pivots 15 which coact with the frame sockets 16 and the hooks 17, the lever 14 has a central depression 44 formed therein for the reception of the adjacent end of the spring 32. The downwardly open sockets with which the knife edges at the free upper ends of the stirrup projections 20 coact, are disposed in opposite sides of the depression 44, and the stirrup plate 19 is provided with a thin and highly flexible sheet metal retainer element 43 secured centrally thereto and coacting with the frame base, see Figs. 2 and 8. The extreme end of the lever 14 remote from the hooks 17 is provided with an integral shelf 45 which is adapted to coact with a flange formed on the lower end of a U-shaped stop member 46 the upper end of which is provided with a similar flange with which an increment differential adjusting screw 47 has screw thread coaction. This screw 47 extends loosely through a hole 48 formed in the terminal board 26 and is surrounded by a helical compression spring 49 coacting with the screw head and which constantly urges the stop element toward the terminal board 26 with any desired force dependent upon the adjustment of the screw 47; and this screw is readily accessible for manipulation upon removal of the cover 37, see Figs. 1, 2 and 3. The screw 47 may be held in adjusted position by a U-shaped spring clip 50 the opposite sides of which spread while an adjustment is being effected but will normally prevent turning of this screw.

The improved snap-action toggle consisting of the toggle plate 21 and the toggle leaf springs 23 constitute an important feature of my invention, and this toggle is operable by the movement of the rigid lever 14 in opposite directions to positively deliver hammer blows or impacts to the movable contacts 29 when moving in either direction. The toggle plate 21 which is swingable relative to the lever hooks 17 on the knife edge 22, is preferably formed of thin and rigid sheet steel and is stiffened along its medial portion by a longitudinal corrugation 52 as shown in Figs. 2, 3 and 5. The elongated toggle leaf springs 23 are straight before insertion but are thereafter longitudinally curved and are preferably formed of relatively thin spring bronze, and while the rear ends 24 of the toggle springs 23 are snugly seated within the frame sockets 25, the front ends 53 thereof are bent to interlock with slots formed in the adjacent end portions of the

toggle plate 21. After assembly of the toggle, the opposite extreme downwardly offset ends 24, 53 of the curved leaf springs 23 are biased away from each other so that the toggle links may be snapped in place, and when they are assembled upon the lever 14 and frame 10 these links will remain in proper position without the use of additional or special fasteners.

The fixed or stationary contacts 28 which are carried by the terminal board 26 above the toggle plate 21, are secured to terminal bushings 54 embedded within the board 26 as shown in Fig. 6, and with which terminal screws 55 are cooperable. The movable contacts 29 which cooperate with the fixed contacts 28 are secured to the free ends of the long resilient contact carrying arms 30 the opposite ends of which are firmly secured to other bushings 56 also embedded within the board 26 as in Fig. 7, by means of screws 57 as shown in Fig. 4. The board 26 is also provided with depending integral walls 33 forming pockets within which the contacts are confined. Other terminal attaching screws 58 coat with the bushings 56 as clearly shown in Fig. 1, and all of the terminal screws 55, 58 are preferably confined within recesses formed in the molded terminal board 26.

The reciprocable pull rod or movable contact actuating member 31 is formed of insulation and has a lower end projection 59 slidably confined in a slot 60 formed in the frame base 11 while its upper end is likewise confined in recesses 61 formed in the terminal board 26, and the medial portion of the member 31 is provided with opposite side notches 62 which engage the adjacent movable contact carrier arms 30, see Figs. 2, 3 and 5. The central portion of the member 31 is also provided with an opening 63 through which an integral projection 64 formed on the toggle plate 21 projects, so that swinging motion of the plate 21 about its knife edge 22 will slide the bar member 31 in the slot 60 and recesses 61 and will thereby swing the movable contact carrier arms 30 about their fastening screws 57.

The upper mid-portion of the rod member 31 is furthermore provided with a depression 65 with which one end of an angular leaf spring 66 contacts and the opposite end of this spring extends through an opening 67 formed in the board 26 as indicated in Figs. 1 and 2. A contact disconnecting lever or crank 68 passes through a medial opening in the spring 66 and is journalled in a groove 69 formed in the board 26, and one end of the crank 68 is provided with a cam 70 cooperable with the member depression 65 through the adjacent end of the spring 66, while the opposite crank end 71 of this lever 68 extends outwardly of the casing 34. By swinging the lever crank 68 a quarter turn in either direction, the bar member 31 may be moved downwardly so as to positively disconnect the movable contacts 29 from the fixed contacts 28 and to maintain the switch in open position, and the spring 66 functions to hold the crank lever 68 in place within the groove 69 and in either position of adjustment.

As previously indicated, the lower end of the adjustable helical compression spring 32 is seated within the central depression 44 of the rigid lever 14, and the upper end of this spring 32 reacts against a washer 73 having a central screw threaded bore engaged by a special screw 74 provided with a flange 75 coating with the top of a central bore 76 formed in the terminal board 75

26, as shown in Fig. 2. The washer 73 has diametrically opposite peripheral projections 77 slidably cooperable with grooves 78 in the bore, and the head of the screw 74 is accessible for manipulation from the top of the terminal board 26 when the cover 37 is removed. By turning the screw 74, the pressure exerted by the spring 32 upon the lever 14 in opposition to the fluid pressure acting upon this lever, may obviously be varied so as to change the range of action of the switch, and the top of the terminal board 26 is preferably provided with indicia as shown, in order to identify the various exposed screws and to indicate the nature of their functioning. A protective shield 80 of insulation is also provided on the side of the frame 10 nearest the conductor openings 35 of the casing 37, and the lower end of this shield 80 is wedged behind a tongue 81 formed integral with the frame wall 13 while the upper shield end has a projection confined within a slot 82 formed in the terminal board 26.

When the various parts of the improved pressure actuated switch have been properly constructed as hereinbefore described, the toggle and contact unit shown in Figs. 4, 5 and 6 should first be assembled by initially mounting the contacts 28, 29, bracket 46, leaf spring 66, and crank lever 68 upon the terminal board 26; by thereafter applying the lever 14, spring 32, toggle links 21, 23, shield 80, and push-pull member 31 in proper position between the frame 10 and terminal board 26; and by finally firmly interconnecting the frame 10 and the board 26 by applying the clamping screws 21. When thus assembling this unit the toggle springs 23 may be connected to the toggle plate end slots, and by distorting the curved leaf springs, these toggle assemblages may be snapped into place and will be retained in proper position without utilizing additional fasteners. The assembled toggle and contact unit may then be secured within the casing 34 and the stirrup 19, diaphragm 18, and enclosure 36 may be simultaneously applied and attached to this casing, whereupon the switch may be connected to the electrical line and motor or other equipment by attaching the conductors to the terminal screws 58, 55 in an obvious manner.

During normal subsequent operation of the improved toggle switch, the contacts 28, 29 will be closed as in Fig. 1 whenever the fluid pressure within the chamber 42 acting upon the diaphragm 18 and through the stirrup 19 against the lever 14, is insufficient to overcome the downward force exerted upon this lever by the main spring 32, so that the motor driven fluid pump will then be operating. As the fluid pressure increases, the stirrup 19 will rise and deflect its thin retainer 43 and will also swing the rigid lever 14 about its pivot projections 15, thereby carrying the connection between the toggle springs 23 and the toggle plate 21 downwardly and stressing the curved leaf springs 23 until this toggle link connection crosses dead center, whereupon the springs 23 immediately become effective to snap the toggle downwardly into its extreme lowermost position. During this rapid downward flexing of the toggle, the bar member 31 will receive a hammer blow from the toggle plate 21 due to the loose fit between the plate projection 64 and the bar slot 63, thus insuring rapid opening separation of the movable contacts 29 from the fixed contacts 28 when a predetermined high pressure has been attained in the chamber 42.

The contacts 28, 29 will remain open as long as the high pressure is maintained within the chamber 42, but when this pressure drops sufficiently so that the spring 32 overcomes the diaphragm lifting effect, then the lever 14 will swing downwardly about its pivot projections 15. This downward swinging of the lever 14 carries the connection between the toggle springs 23 and the toggle plate 21 upwardly and stresses the leaf springs 23 until the toggle link connection again crosses dead center, whereupon the springs 23 immediately become effective to snap the toggle upwardly into its extreme uppermost position. During this rapid upward flexing of the toggle, the bar member 21 will again receive a hammer blow from the projection 64 of the toggle plate 21, thus producing impact closing of the movable contacts 29 and stressing the resilient movable contact carrying arms 30 sufficiently so that they will bend and produce a desirable wiping action upon the fixed contacts 28. This stressing of the spring arms 30 positively prevents rebound of the movable contacts 29 and also augments subsequent opening motion thereof.

Both the opening and closing of the contacts 28, 29 are thus effected rapidly, positively and with a decided snap and wiping action, and without permitting the toggle links to hang on dead center; and whenever the lever 14 is swung upwardly about the projections 15, the rear shelf 45 of this lever will swing downwardly so as to engage the lower flange of the bracket 46. This engagement causes the U-shaped bracket 46 to move downwardly and to compress the spring 49, and the force exerted by this spring 49 aids the main spring 32 in opposing the fluid pressure so that greater fluid pressure is required to open the contacts than if the spring 49 were omitted. The screw 47 may be adjusted to vary the bracket retaining pressure and the degree of compression of the spring 49, thereby increasing or decreasing the pressure differential accordingly, and the main heavier spring 32 may be adjusted by manipulation of the adjusting screw 14 so as to simultaneously vary both the contact opening and closing pressure or the range of action of the switch. The auxiliary spring 49 thus functions to modify the action of the main spring 32 in order to secure accurate performance, and both of the spring adjustments may be conveniently effected with the aid of a screw driver upon removal of the cover 37 and while the switch is in normal use. During adjustment of the main spring 32 the projections 77 of the washer 73 coat with the grooves 78 to prevent rotation of the washer, and the spring clip 50 also normally prevents rotation of the screw 47.

In order to positively disconnect the movable contacts 29 from the fixed contacts 28, it is only necessary to give the crank 71 of the lever 68 a quarter turn in either direction. Such partial rotation of the crank lever 68 causes the cam 61 to engage the adjacent end of the retaining spring 66 and thereby presses this spring end downwardly against the bottom of the medial recess 65 in the bar member 31, thus forcing the member downwardly and positively opening both of the movable contacts 29. The contacts 28, 29 will then remain positively separated until the crank lever 68 is again restored to the position shown in Figs. 1, 2 and 5, and such disconnection may be quickly and conveniently effected without removing the cover 37. Besides providing a pivot bearing for the lever 68, the leaf

spring 66 is formed to positively hold this lever in any adjusted position regardless of the disposition of the switch unit.

From the foregoing detailed description of the construction and operation of my improved pressure actuated toggle switch, it should be apparent that I have in fact provided a switch assemblage which is simple, compact and durable in construction, and which is also highly efficient in operation and flexible in its adaptations. The improved toggle mechanism functions with a snap-action to produce positive impact closing and opening of the contacts; and besides being sensitive and dependable in operation, this toggle may be readily assembled without the use of special fasteners. The loose fits between the toggle plate 21 and the slot 63 of the push-pull member 31, enables the toggle to build up sufficient momentum when crossing dead center in either direction so as to cause the member 31 to open and close the contacts 29, 29 with a snap and impact action, and the knife-edge pivot edges of the toggle links eliminate excessive friction, thereby causing the short toggle plate 21 and long flexible springs 23 to function with utmost precision. The upward biasing of the resilient contact carrying fingers 30 is also important since it provides contact pressure while the fluid pressure is building up to the tripping point and the force exerted by the toggle upon the contacts approaches and reaches zero value. This biasing of the arms or fingers 30 also prevents fluttering of the contacts, and the use of two toggle springs 23 also augments the flexibility of the improved toggle which has proven highly satisfactory and successful in actual use.

The various essential parts of the improved switch mechanism may also be accurately constructed with the aid of punches and dies, and simple molds; and they may also be easily assembled or dismantled if necessary. The thin flexible retainer 43 cooperates with the stirrup 19 to prevent the same from being swung laterally by the diaphragm 18, and does not unduly interfere with the vertical motion of the stirrup. All parts of the pressure actuated switch are normally well protected while still being quickly accessible for inspection and adjustment, and the adjusting screws 14, 47 afford a wide range of pressure and differential setting and positively maintain such settings with utmost precision. The improved switches due to their extreme simplicity may be manufactured at moderate cost for diverse purposes, and the final assemblages are so compact that they may be readily installed in cramped quarters.

It should be understood that it is not desired to limit this invention to the exact details of construction and operation of the typical pressure actuated toggle switch herein shown and described, for various modifications within the scope of the appended claims may occur to persons skilled in the art.

I claim:

1. In combination, a frame, a rigid lever having one end portion swingably suspended from said frame and also having laterally spaced hooks at its opposite end, means for applying fluid pressure to the medial portion of one face of said lever, an elongated toggle plate having a longitudinal edge swingably cooperable with said hooks, a toggle leaf spring coacting with each of the opposite ends of said toggle plate near said hooks but remote from said edge, the ends of said leaf springs remote from said toggle plate

being pivoted on said frame, fixed and movable contacts mounted on said frame remote from said lever, and a reciprocable member operatively connecting the swinging portion of said toggle plate with said movable contacts.

2. In combination, a frame, a rigid lever having one end portion swingably suspended from said frame and also having laterally spaced hooks at its opposite end, means for applying fluid pressure to the medial portion of one face of said lever, an elongated toggle plate having a longitudinal edge swingably cooperable with said hooks, a toggle leaf spring coacting with each of the opposite ends of said toggle plate near said hooks but remote from said edge, the ends of said leaf springs remote from said toggle plate being pivoted on said frame, fixed and movable contacts mounted on said frame remote from said lever, a reciprocable member operatively connecting the swinging portion of said toggle plate with said movable contacts, and an adjustable compression spring for applying predetermined pressure to the opposite face of said medial lever portion.

3. In combination, a frame, a rigid lever having one end portion swingably supported on said frame and also having laterally spaced hooks at its opposite end, means for applying fluid pressure to the medial portion of the bottom of said lever, an elongated toggle plate having a longitudinal edge swingably cooperable with said hooks, an elongated toggle leaf spring coacting with each of the opposite ends of said toggle plate near said hooks but remote from said edge, the ends of said leaf springs remote from said toggle plate coacting with said frame, a terminal board mounted on said frame, fixed and movable contacts carried by said board remote from said lever, and a reciprocable bar member slidable in said frame and said board and operatively connecting the swinging portion of said toggle plate with said movable contacts.

4. In combination, a frame, a rigid lever having one end portion swingably supported on said frame and also having laterally spaced hooks at its opposite end, means for applying fluid pressure to the medial portion of the bottom of said lever, an elongated toggle plate having a longitudinal edge swingably cooperable with said hooks, an elongated toggle leaf spring coacting with each of the opposite ends of said toggle plate near said hooks but remote from said edge, the ends of said leaf springs remote from said toggle plate coacting with said frame, a terminal board mounted on said frame, fixed and movable contacts carried by said board remote from said lever, a reciprocable bar member guided in said frame and said board and operatively connecting the swinging portion of said toggle plate with said movable contacts, and an adjustable compression spring interposed between said board and the top of said lever for applying predetermined pressure to the latter.

5. In combination, a frame having opposite side walls and an end wall, a rigid lever having one end swingably suspended from said side walls and also having laterally spaced hooks at its opposite end, means for applying fluid pressure to the bottom of said lever, an elongated thin toggle plate having a longitudinal edge swingably confined within said hooks, a flexible toggle leaf spring coacting with each of the opposite ends of said toggle plate near said hooks but remote from said edge, the ends of said leaf springs remote from said toggle plate pivotally coacting with said end wall, fixed and movable contacts;

mounted on said frame remote from said lever, and a reciprocable member guided in said frame and operatively connecting the swinging portion of said toggle plate with said movable contacts.

5. In combination, a frame having spaced side walls and an intervening end wall, a rigid lever having one end swingably suspended from said side walls also having laterally spaced hooks at its opposite end, means for applying fluid pressure to the bottom of said lever, an elongated thin toggle plate having a longitudinal edge swingably confined within said hooks, a flexible toggle leaf spring coacting with each of the opposite ends of said toggle plate near said hooks but remote from said edge, the ends of said leaf springs remote from said toggle plate swingably coacting with said end wall, a terminal board mounted on said side walls, fixed and movable contacts carried by said board remote from said lever, a reciprocable bar member slidable in said board and said frame and operatively connecting the swinging portion of said toggle plate with said movable contacts, and an adjustable compression spring interposed between said board and the top of said lever for applying predetermined pressure to the lever in opposition to the fluid pressure.

7. In combination, a frame having end sockets, a rigid lever having one end portion swingably suspended from said frame and also having laterally spaced hooks at its opposite end, means for applying fluid pressure to one face of said lever, an elongated toggle plate having a longitudinal edge swingably confined within said hooks, a longitudinally curved toggle leaf spring pivotally confined within each of the opposite ends of said toggle plate near said hooks but remote from said edge, the ends of said leaf springs remote from said toggle plate being pivoted in said sockets and the opposite ends of each spring being resiliently biased toward said toggle plate and sockets, fixed and movable contacts mounted on said frame remote from said lever, and a reciprocable bar member operatively connecting the swinging portion of said toggle plate with said movable contacts.

8. In combination, a frame having side walls provided with notches and an end wall provided with sockets, a lever having one end swingably confined in the side wall notches and also having laterally spaced hooks at its opposite end, means for applying fluid pressure to the bottom of said lever, an elongated toggle plate having a longitudinal edge swingably confined within said lever hooks, a toggle leaf spring pivotally confined within each of the opposite ends of said toggle plate near said hooks but remote from said edge, the ends of said leaf springs remote from said toggle plate being swingably confined within the end wall sockets, fixed and movable contacts mounted on said frame remote from said lever, and a reciprocable bar member slidably cooperable with said frame and operatively connecting the swinging portion of said toggle plate with said movable contacts.

9. In combination, a frame, a lever having one end swingably suspended from said frame and also having laterally spaced hooks at its opposite end, means for applying fluid pressure to the bottom of said lever, an elongated toggle plate having a longitudinal edge swingably confined within said lever hooks, a toggle leaf spring pivotally confined within each of the opposite ends of said toggle plate near said hooks but remote from said edge, the ends of said leaf

springs remote from said toggle plate being swingably associated with said frame, fixed and movable contacts mounted on said frame remote from said lever, and a reciprocable bar member slidably cooperable with said frame and loosely connecting the swinging portion of said toggle plate with said movable contacts.

10. In combination, a frame, a rigid lever having one end portion swingably supported on said frame and also having laterally spaced hooks at its opposite end, means for applying fluid pressure to the medial portion of said lever, an elongated toggle plate having a longitudinal pivot edge swingably cooperable with said hooks and being provided with a central projection on its opposite edge, an elongated toggle leaf spring coacting with each of the opposite ends of said toggle plate near said opposite edge but remote from said pivot edge, the ends of said leaf springs remote from said toggle plate pivotally coacting with said frame, fixed and movable contacts carried by said frame remote from said lever, and a reciprocable bar member slidably in said frame and said board and loosely connecting the projection on said toggle plate with said movable contacts.

11. In combination, a frame, a rigid lever pivotally suspended from the frame and having laterally spaced hooks remote from its pivots, means for applying fluid pressure to said lever between the pivots and hooks, an elongated rigid toggle plate having a pivot edge swingably cooperable with said hooks and also having a projection at its swinging opposite edge, an elongated toggle leaf spring coacting with each of the opposite ends of said toggle plate near said opposite edge but remote from said pivot edge, the ends of said leaf springs remote from said toggle plate pivotally coacting with said frame, a terminal board mounted on said frame, fixed contacts secured to said board, movable contacts carried by leaf springs secured to said board and biased toward said fixed contacts, and a reciprocable bar member guided in said frame and said board and having a slot loosely coacting with said toggle plate projection and with said contact carrying springs.

12. In combination, a frame having sockets, a rigid lever having pivots swingably suspended from said sockets and also having hooks remote from said pivots, means for applying fluid pressure to said lever, a rigid toggle plate having a knife edge pivoted within said hooks, an elongated flexible toggle leaf spring pivotally confined within each of the opposite ends of said toggle plate remote from said pivot edge and coacting with said frame, fixed and movable contacts supported upon said frame remote from said lever, and a reciprocable bar member loosely connecting the swinging medial portion of said toggle plate with said movable contacts.

13. In combination, a frame, a rigid lever swingably suspended from said frame, means for applying pressure to said lever to swing the same, a terminal board mounted upon said frame remote from said lever, fixed and movable contacts carried by said terminal board, a toggle operable by said lever, a reciprocable bar slidably in said frame and said terminal board and operatively connecting said toggle with said movable contacts, an angular leaf spring element having one end portion secured to said terminal board and a second end portion cooperable with an end of said bar, and a cam member journaled in the medial portion of said spring ele-

ment and coacting with said bar through said second end portion to maintain said movable contacts open in opposition to said toggles.

14. In combination, a frame, a rigid lever swingably suspended from said frame, means for applying pressure to said lever to swing the same, a terminal board mounted upon said frame remote from said lever, fixed and movable contacts carried by said terminal board, a dual link toggle interposed between said frame and said lever and having one link provided with a projection extending beyond the connection between its links, and a bar slidably within said frame and said terminal board and having slots loosely coacting with said link projection and with said movable contacts.

15. In combination, a frame, a rigid lever swingably suspended from said frame, means for applying pressure to said lever to swing the same, 20 a terminal board mounted upon said frame remote from said lever, fixed and movable contacts carried by said terminal board, said movable contacts being carried by resilient arms biased toward the fixed contacts, a toggle interposed between said frame and said lever and having a link plate provided with a swinging projection, and a reciprocable bar having slots loosely coacting with said arms and with said link projection.

16. In combination, a frame, a rigid lever having one end portion swingably suspended from said frame and being provided with a hook at its opposite end, means for applying fluid pressure to the medial portion of said lever, a toggle plate 35 having a knife edge swingably cooperable with said hook, medially curved toggle leaf spring having one off-set end coacting with said toggle plate near said hook but remote from said knife edge, the opposite end of said toggle leaf spring also being off-set and having knife edge pivotal coaction with said frame, fixed and movable contacts mounted on said frame, and a reciprocable member operatively connecting a swinging portion of said toggle plate opposite from said knife edge with said movable contact.

17. In combination, a frame, a rigid lever having one end portion swingably suspended from said frame and being provided with a hook at its opposite end, means for applying fluid pressure to the medial portion of one face of said lever, a toggle plate having a knife edge swingably cooperable with said hook, a medially curved toggle leaf spring having one off-set end pivotally coacting with said toggle plate near said hook but remote from said knife edge, the opposite end of said toggle leaf spring also being off-set and having knife edge coaction with said frame, fixed and movable contacts mounted on said frame, a reciprocable member operatively connecting a swinging portion of said toggle plate opposite from said knife edge with said movable contact, and an adjustable spring for applying predetermined pressure to the opposite face of said medial rigid lever portion.

18. In combination, a frame, a rigid lever having one end portion swingably suspended from said frame and being provided with a hook at its opposite end, means for applying fluid pressure to the medial portion of one face of said lever, 70 a toggle plate having a knife edge swingably cooperable with said hook, a medially curved toggle leaf spring having one off-set end pivotally coacting with said toggle plate near said hook but remote from said knife edge, the opposite end of said toggle leaf spring also being off-

set and having knife edge coaction with said frame, a terminal board mounted on said frame, fixed and movable contacts carried by said board, a reciprocable bar member slidable in said frame and said terminal board and operatively connecting a swinging portion of said toggle plate opposite from said knife edge with said movable contact, and adjustable means for applying predetermined pressure to the opposite face of said medial rigid lever portion.

10 GILBERT H. HANSEN.
